UNITED STATES PATENT OFFICE.

SAMUEL H. TINSMAN, OF MORRIS, ILLINOIS, ASSIGNOR, BY MESNE ASSIGNMENTS, TO INTERNATIONAL HARVESTER CORPORATION, A CORPORATION OF NEW JERSEY.

DISK ATTACHMENT.

1,185,857.

Specification of Letters Patent. Patented June 6, 1916.

Application filed March 5, 1913. Serial No. 752,171.

To all whom it may concern:

Be it known that I, SAMUEL H. TINSMAN, a citizen of the United States, residing at Morris, in the county of Grundy and State 5 of Illinois, have invented certain new and useful Improvements in Disk Attachments, of which the following is a full, clear, and exact specification.

My invention relates to disk attachments. 10 It has for its object to support in an improved manner a disk of the type used in cultivators, plows, harrows, grain drills or the like.

Further objects of my invention are to 15 attach the disk to its support in an improved manner, to increase the facility of assembly and removal of the parts, to prevent the entry of dirt or grit into the bearing surfaces thereof, and to improve and simplify 20 the construction of the disk bearing and its supporting and attaching means.

I attain these objects by providing an improved disk support and an improved bearing member coöperating therewith and with 25 the disk, and attached to the disk support in an improved manner.

In order to disclose my invention clearly and fully, I have illustrated one embodiment thereof in the accompanying drawings. 30 It is to be understood, however, that the construction shown herein is susceptible of modification.

Figure 1 is an end elevation of the disk attached to its support; Fig. 2 is a similar 35 view showing the disk, its bearings, and its attaching means in section; Fig. 3 is a top plan view of one of the means for attaching the disk to its support; Fig. 4 is a side elevation of the same; Fig. 5 is a top plan view 40 of the disk bearing member; Fig. 6 is an end elevation of the same.

The construction shown, when broadly considered, comprises a disk support 1 adapted to be carried in any suitable manner upon a frame of any desired construction and carrying upon its lower end a disk 2 in an improved manner, hereinafter described.

The support or shank 1, as shown in Fig. 50 2, is preferably of integral construction and of cylindrical cross section. As shown herein, it is provided at its lower end with a laterally extending angularly disposed elbow or arm 3 protruding substantially at 55 an angle of 70° from the body portion there-

of and in an upward direction. Upon this elbow or arm 3 is seated the bearing member 4 carrying the disk 2. This bearing member is likewise preferably of integral construction and is provided with an elongated longitudinally extending bore 5 of cylindrical cross section adapted to receive the extension 3 on the shank 1 and be freely rotatable thereon.

As shown in Fig. 2, the end of the bearing 65 4 adjacent the body portion of the support 1 is enlarged and provided with an annular shoulder 6 adapted to be received in a circular opening in the center of the disk 2. The disk itself is attached to this 70 enlarged portion by a plurality of rivets 7. In a preferred form the enlarged end of the bearing 4 is also of substantially cylindrical cross section and has a greater diameter than the shoulder 6; a second annular flange 75 8 being provided upon the periphery thereof for a purpose hereinafter described. As shown in Figs. 2 and 5, the end of the bearing member 4 adjacent the support 1 is slightly rounded at 9. Coöperating with 80 this bearing member 4 and adapted to fit over the flange 8 thereon to lock the member 4 to the support in such a manner as to permit the free rotation of the bearing, is a removable attaching member 10. This attaching member 10 is shown to be provided with a radially extending perforated lug 11 at the back of the same which is adapted to be moved freely up and down upon the body 85 portion 1 of the support.

As shown in Figs. 3 and 4, the body portion 90 of this member 10 is substantially semi-cylindrical in cross section, and of larger diameter than the flange 8 upon the bearing member 4. It is further provided with an inwardly dished recess 12 adapted to receive the rounded end 9 of the bearing member, and a short downwardly extending annular lip or flange 13 which protrudes substantially at right angles to the side wall 100 of this recess and is adapted to engage the side wall of the flange 8 and rest upon the surface of the enlarged end of the bearing 4 adjacent the same. In order to facilitate the movement of the parts and allow a more 105 compact construction, the portion of the member 10 adjacent the support 1 is cut away or dished at 14. It is here also to be noted that this member, when locking the member 4 in place is also itself locked 110

against accidental movement on the shank 1. The member 10 is also provided, as shown in Fig. 4, with an upwardly extending slot 15 having converging walls so that 5 downwardly extending portions at the sides thereof may straddle the elbow 3 and inclose the upper portion of the bearing member 4.

It is to be noted that in my improved construction, the disk is supported in such a 10 manner as to engage the ground at the most satisfactory angle to give the desired tilling effect. The parts of the attachment are further readily assembled by first slipping the bearing member 4 carrying the disk 2, upon 15 the end 3 of the support 1 and then sliding the attaching member 10 downwardly on the support 1 until it straddles the portion 3 thereof and its lip 13 incloses the flange 8 on the bearing. To remove the parts it is 20 obviously only necessary to move the locking member 10 upward to release the bearing member so that the latter may be withdrawn. In this assembled position, it is to be noted that both the disks 2 and the 25 bearing 4 are freely rotatable upon the portion 3 of the support and that the thrust is so taken upon the end of the extension thereon as to entirely remove any thrust upon the vertical portion of the support 30 and to eliminate the necessity for a collar thereon. Obviously, by placing grease or any other suitable lubricant in the bore or chamber 5 of the bearing member, the bearing surfaces may be lubricated to the desired 35 degree without making it necessary to replenish the supply except at long intervals. It is here also to be noted that by my improved construction of bearing member, I am able to eliminate not only all protruding 40 oil cups and the like, but am also able to eliminate all possibility of grit or dust entering the bearing from above. Attention is further directed to the fact that the attaching member 10 not only serves to permit 45 the parts to be readily assembled or separated when desired, but at the same time serves to deflect the dirt or grit from the bearing surfaces which it straddles. It is further to be noted that in this construction 50 no dirt can enter the bearing from the support 1 since it is not only deflected by the attaching member 10 but is also unable to climb upward toward the bearing on the upwardly disposed end of the support 1 in 55 opposition to the pull of gravity. Further, if any dirt should happen to be thrown upward on the elbow 3, it will likewise be quickly dislodged from the rounded surface thereof by the vibration of the machine as 60 it moves over the ground.

On account of the angle of the axle with respect to the shank portion, the disk in operation will be forced toward the shank, with the result that a greater portion, if 65 not all, of the wear and strain will be thrown

on the end of the axle and its engaging hub portion. The action of the disk, therefore, in tilling is to work inwardly on the axle and not outwardly as in devices heretofore used. With this construction I am enabled 70 to maintain the disk in proper position at all times without the necessity of employing permanent fasteners for the locking member. This is so because of the relative positions of the member 10 with respect to the 75 flanged hub portion of the disk. Obviously, in order to raise the locking member it is necessary that the disk be moved slightly outward on its axle, and this movement will be prevented when in operation by engagement of the disk in the ground. It is only during the operative periods of the disk that the locking member is susceptible to displacement, and this is because of the action 80 of clods of dirt and other obstructions in 85 the field striking against it. At any other time gravity and frictional engagement are sufficient to cause the locking member to remain in place and thus prevent the disk from working off. The disk, therefore, becomes readily demountable for sharpening or substitution purposes without attention 90 on the part of the operator to permanent fasteners of any kind.

While I have described in this application one form of my invention, it is of course to be understood that the embodiment thereof shown herein for purposes of illustration is susceptible of modification without departing from its spirit.

What I claim as my invention, and desire to secure by Letters Patent, is:

1. In a disk attachment, a vertical shank having an extension protruding therefrom at an acute angle, a disk rotatably mounted on said extension in a manner to automatically retain its position thereon when in operation, and a locking member for said disk carried on the shank and pressed between the shank and disk.

2. In a disk attachment, a vertical support, an extension protruding therefrom, a rotatable member inclosing one end of said extension, a disk carried on said rotatable member, a flanged member on the inner end of said rotatable member, and a locking member on the vertical support to engage with the flanged member for holding the disk in position, said locking member in turn being held in locked position by its co-operating members.

3. In a disk attachment, a vertical support, an extension protruding therefrom, a rotatable member on said extension, a disk carried on the rotatable member in position to be forced inwardly when in operation, a flanged hub on the inner side of the disk, and means mounted on said support to engage with the flanged hub and hold it against outward movement, said

holding means in turn being held by its associated members.

4. In a disk attachment, a vertical support, an extension thereon, a rotatable member inclosing one end of said extension, a disk on said rotatable member, and means movable along said support for locking said rotatable member against separation and held automatically in locked position when

10 said disk is in operation.

5. In a disk attachment, a shank having an extension protruding at an angle thereto, a bearing member rotatably mounted on said extension, and an attaching member movable 15 on said shank and locking said bearing member thereto, said attaching member when locking said bearing member in position automatically locking itself against accidental movement on said shank.

20 6. In a disk attachment, a shank having an extension protruding therefrom, a bearing member rotatably mounted on said extension and having an enlarged portion adjacent said shank, a disk carried on said bearing member, and an attaching member freely 25 movable along said shank to engage with said bearing member for locking the same on said extension and automatically held in locked position when said disk is in operation.

30 7. In a disk attachment, a shank having an extension protruding at an angle therefrom, a rotatable member carried on said extension and inclosing one end of same, a disk carried on said rotatable member and operating in a manner to confine the frictional engagement between the extension and rotatable member to the ends thereof and a locking member to engage with the rotatable member movable on the shank and normally held pressed between the rotatable member and the shank.

40 8. In a disk attachment, a vertical shank having an extension protruding therefrom

at an angle less than a right angle, a bearing 45 member on said extension inclosing one end of same, and a disk carried on said bearing member and forced inward when in operation, and a locking member carried on the shank and positioned normally between the 50 shank and bearing member and held thereby said shank and bearing member under certain conditions.

9. In a disk attachment, a vertical support, an axle on said support, a bearing 55 member carried on said axle and having an enlarged flanged portion on its inner end, a disk on said bearing portion, and a locking member on said support for holding said bearing member in position and itself held 60 against movement by frictional engagement between the support and flanged end of the bearing member.

10. In a disk attachment, a vertical support, an extension thereon protruding at an angle less than a right angle, a bearing member carried on said extension and provided with an enlarged flanged portion on its inner end, a disk on said bearing member, and a locking member movable on said support 70 for locking said bearing member in position and itself held against movement by frictional engagement between said support and the flanged end of the bearing member.

11. In a disk attachment, a support, a 75 disk carrying bearing member mounted thereon, and a locking member, said support, bearing and locking members mutually interlocking each other under certain conditions.

Chicago, Ill., Feb. 21, 1913.

In testimony whereof I affix my signature, in the presence of two witnesses.

SAMUEL H. TINSMAN.
